UNITED STATES PATENT OFFICE.

WILLIAM LEONHARDT, OF BALTIMORE, MARYLAND.

DESIGN FOR A WAGON-BODY.

SPECIFICATION forming part of Design No. 34,488, dated May 7, 1901.

Application filed March 2, 1901. Serial No. 49,662. Term of patent 7 years.

To all whom it may concern:

Be it known that I, WILLIAM LEONHARDT, a citizen of the United States, residing at Baltimore, Maryland, have invented and produced a new and original Design for a Wagon-Body, of which the following is a specification, reference being had to the accompanying drawing, which is a perspective view of my new design.

10 The body as seen from its under side is rectangular in shape, and its back A is straight and vertical. The top B, except the overhang C, which is curved downward, is longitudinally straight and parallel with the bottom D; but in a transverse direction it is rounded or downwardly curved. The upper portion E of the front is vertical, and its sides are connected with the overhang C by the hollow curves F. The lower portion G of the front

15

projects beyond the upper portion E and is straight from the bottom to the point a. Above this it is united to the part E by a reverse curve H.

The sides I of the body are straight, vertical, and parallel one with the other.

Having described my invention, what I claim as new, and desire to secure by Letters Patent, is—

20 The design for a wagon-body, as herein shown and described.

25 In testimony whereof I have signed my name to this specification in the presence of two subscribing witnesses.

WILLIAM LEONHARDT.
